UNITED STATES PATENT OFFICE.

GEORGE H. GILMAN, OF CLAREMONT, NEW HAMPSHIRE, ASSIGNEE, BY MESNE ASSIGNMENTS, TO SULLIVAN MACHINERY COMPANY, OF BOSTON, MASSACHUSETTS, A CORPORATION OF MASSACHUSETTS.

PRESSURE-ACTUATED TOOL.

1,143,534.

Specification of Letters Patent. Patented June 15, 1915.

Original application filed November 13, 1908, Serial No. 462,402. Divided and this application filed October 24, 1910. Serial No. 588,618.

To all whom it may concern:

Be it known that I, GEORGE H. GILMAN, a citizen of the United States, and a resident of Claremont, county of Sullivan, and State of New Hampshire, have invented an Improvement in Pressure-Actuated Tools, of which the following description, in connection with the accompanying drawings, is a specification, like letters on the drawings representing like parts.

This invention relates to pressure-actuated tools, being more particularly concerned with the provision of improved feeding devices for such tools and the improved construction of such devices.

This application is a division of my prior co-pending application, Serial No. 462,402, filed November 13, 1908.

The invention will be best understood by reference to the following description when taken in connection with the accompanying illustration of one specific embodiment thereof while its scope will be more particularly pointed out in the appended claims.

In the drawings: Figure 1 shows in side elevation, partly broken away, a pressure-fed hammer drill embodying one form of my invention; Fig. 2 is a central, sectional elevation of a portion of the supporting or abutting end of the feed cylinder; Fig. 3 is a sectional elevation on the line 3-3 in Fig. 2; Fig. 4 is a plan, on an enlarged scale, of the head block and its connections to the tool and feed cylinders; Fig. 5 is a longitudinal section in elevation of the same taken on the line 5-5 in Fig. 4.

Referring to the drawings and to the embodiment of my invention which I have there disclosed for illustrative purposes, I have there shown a pneumatic tool, herein of the hammer drill type, having the cylinder 1 so connected to suitable pressure-actuated feeding apparatus that the pressure fluid supplied thereto through the pipe 2 acts not only reciprocatively to move the hammer piston 3 against the shank of the cutter bit or drill 4, but also acts initially to advance the tool toward the work and hold the drill forcibly pressed against the same while the tool is in operation, all as represented in Fig. 1.

While pressure-actuated feeding means of

any suitable construction may be employed, herein I have provided a feeding cylinder 5 adapted to coöperate with a suitable feeding piston 5 (see Fig. 5) therein contained. It is, of course, immaterial which of the cylinder and piston members is connected to the tool, but in either event the remaining part serves to support the apparatus either by abutment against a wall or other support. In the present instance the piston 6 serves as the abutting or supporting member, the cylinder being rigidly secured to the tool to move therewith on the support which is provided by the fixed piston.

In the present form of apparatus the pressure fluid for actuating the feed and the tool is controlled through a throttle valve, 7, the handle for which is represented at 7, such valve being mounted in the connecting piece 8 interposed between and rigidly secured to the feed cylinder 5 and the tool cylinder 1.

In devices of this class great trouble has been experienced from the employment of threaded joints for securing the feed and tool parts together and difficulty has been found in providing an attachment suitable for holding the parts securely together while capable of withstanding the severe vibratory strains to which they are subjected when used in the mine.

In the present construction I have provided accurately fitting slip joints between the feed cylinder and the connecting piece on the one side and the tool cylinder and connecting piece on the other, and have also provided means for clamping such parts securely together without the use of threaded joints between the parts, and preferably through the employment of tapered or conical clamping means.

Referring more particularly to the construction shown in Figs. 4 and 5, the forward or inner end of the feed cylinder is provided with outwardly flared tapering walls 9, and the same is fitted over a reduced projecting portion 10 of the connecting piece, a packing ring 11 being preferably employed to make the slip joint thus provided pressure tight. At the opposite or forward end of the connecting piece there is provided the shell 12 fitted about and slipped over the valve block 13 and its end plate 14.

and also over a short end portion of the cylinder 1. The latter, closely adjacent the shell portion of the connecting piece 8 is also provided with tapered walls 15, similar to the tapered portion 9 on the feed cylinder, but reversely arranged. With the parts in the position shown they are all clamped rigidly together by means of the clamping collars 16 and 17, which latter have tapered 5 openings to fit over the tapered walls of the feed cylinder and tool cylinder, respectively, and are united and clamped together by means of the tie bolts 18 and the clamping nuts 19, the bolts passing through lateral 10 ears on the clamping collar. This provides a perfectly rigid connection for the feed cylinder, tool cylinder and the intervening connecting piece without the use of threaded joints, and affords a connection capable of 15 holding together under the most severe 20 usage.

Referring now to Figs. 1, 2 and 3, at the opposite or supporting end of the feed cylinder, provision is made for a plug or guiding piece for the piston rod inserted in the end of the cylinder and there retained without the use of threaded joints or threaded 25 connections. While this may be effected in various ways, in the present instance there 30 is provided a plug 20 provided with a head and having a reduced portion fitting the end of the cylinder into which it is stepped. The plug not only closes the end of the cylinder but provides a guide for the end of 35 the piston rod 21, which latter terminates in the foot or pivoted end 22 adapted to abut against a fixed support, such as the wall shown in Fig. 1.

In assembling the apparatus the plug is 40 inserted and a U-shaped retaining device is then driven into suitably drilled transverse holes in the walls of the cylinder and of the plug. The projecting ends of the retaining member (represented in dotted line, Fig. 3) 45 are then bent over against the cylinder, as there shown, thus effectually locking the piece against displacement no matter how great the vibration may be to which the apparatus is subjected. On the other hand, 50 if it is desired to dismantle the apparatus, or remove the piston for any purpose, the plug may be withdrawn by straightening out the ends of the insertion member or key and withdrawing the latter to release the 55 plug. Preferably means are provided, such as the relief passage 24 for connecting the rearward end of the feed cylinder with the atmosphere.

While I have herein shown and described 60 for the purpose of illustration one concrete form or embodiment of my invention, it is to be understood that the same is not limited to the details of construction, or relative form or arrangement of parts, or to the 65 application herein made of the various fea-

tures thereof, but that the same may be modified within wide limits without departing from the spirit of the invention.

Having thus described my invention, what I claim is:

1. In a pressure-fed tool, the combination with a feed cylinder and tool cylinder, an intermediate connecting member, and clamping means directly attached to the feed cylinder and tool cylinder and acting to draw 70 both against the intermediate member.

2. In a pressure-fed tool, the combination with a feeding member, a tool member, said members having connection by means of slip joints, clamping collars encircling said feeding member and tool member respectively and means connecting said collars to each other for clamping the said members together.

3. In a pressure fed tool, the combination with a feeding member provided with a tapered end, a tool member also having a tapered end, tapered means adapted to seat on said ends and connect the one member to the other, an intermediate connecting section and means for clamping said members to their tapered seats.

4. In a pressure fed tool, the combination with a feeding member provided with an abutment, a tool cylinder provided with an 95 abutment, a connecting piece to which said member and cylinder are both connected by means of slip joints, and clamping means including collars engaging said abutments, respectively, for clamping said cylinder and 100 feed member to said connecting piece.

5. In a pressure-actuated tool, the combination with a hammer tool having a cylinder, a tool feeding apparatus including a cylinder member and a coöperating piston 105 member, an intermediate connecting member having a slip joint connection both with said feed cylinder and said tool cylinder, a throttle valve seated in said connecting member the latter being provided with pressure fluid passages leading both to said feed cylinder and said tool cylinder, both said feed cylinder and said tool cylinder being provided with circumferential projections having longitudinally tapered surfaces, a 110 clamping collar seated against the tapered projection on the tool cylinder, a second clamping collar seated against the tapered projection on the feed cylinder, and tie bolts connecting said clamping collars and 115 serving to unite the feed cylinder, connecting member and tool cylinder.

6. In a pressure actuated tool, the combination with a hammer tool having a cylinder, a tool feeding apparatus including a 125 cylinder member and a coöperating piston member, an intermediate connecting member having a slip joint connection both with said feed cylinder and said tool cylinder, a throttle valve seated in said connecting member, 130

the latter being provided with pressure fluid passagess leading both to said feed cylinder and said tool member, both said feed cylinder and said tool cylinder being provided with 5 circumferential projections, a clamping collar seated against the projection on the tool cylinder; a second clamping collar seated against the projection on the feed cylinder and tie bolts connecting said clamping collars and serving to unite the feed cylinder, 10 connecting member and the tool cylinder.

7. In a pressure actuated tool, the combination with a hammer tool having a cylinder, a tool feeding apparatus including a cylinder member and a coöperating piston member, an intermediate connecting member having a slip joint connection both with said feed cylinder and said tool cylinder, a throttle valve seated in said connecting member, the latter being provided with 15 pressure fluid passages leading both to said feed cylinder and said tool cylinder, and means including a plurality of tie rods for clamping together the feed cylinder, connecting member and tool cylinder.

8. In a pressure-actuated tool the combination with a hammer tool, a tool feeding apparatus including a feed member, an intermediate connecting member having a slip joint connection both with said feed member and with said hammer tool, a throttle valve seated in said connecting member, the latter being provided with pressure fluid passages leading both to said feed cylinder and said tool cylinder, and means including a plurality of tie rods for clamping together the 20 feed cylinder, connecting member and tool cylinder.

feed member, connecting member and hammer tool.

9. In a pressure-actuated tool, the combination with a hammer tool, a tool feeding 40 apparatus including a feed member, an intermediate member, a throttle valve seated therein, said connecting member being provided with pressure fluid passages leading both to the feed cylinder and tool cylinder, 45 and clamping means including a plurality of tie rods directly connected to the feed member and hammer tool for drawing both against the connecting member and uniting the feed member, connecting member and hammer tool.

10. In a pressure actuated tool, the combination with a hammer tool having a cylinder, a tool feeding apparatus including a cylinder member and a coöperating piston 55 member, an intermediate connecting member having a slip joint connection both with the feed cylinder and the tool cylinder, said connecting member being provided with pressure fluid passages, and clamping means 60 including a plurality of tie rods and collars engaging said feed cylinder and tool cylinder for clamping together the feed cylinder, connecting member and tool cylinder.

In testimony whereof, I have signed my 65 name to this specification, in the presence of two subscribing witnesses.

GEORGE H. GILMAN.
